UNITED STATES PATENT OFFICE

THOMAS W. SMALL, OF HUNTINGTON, INDIANA, ASSIGNOR TO THE CAPEHART CORPORATION, OF FORT WAYNE, INDIANA, A CORPORATION

AUTOMATIC PHONOGRAPH FOR NONUNIFORM RECORDS

Application filed April 14, 1930. Serial No. 443,946.

This invention relates to an automatic phonograph. More particularly it relates to a phonograph in which a plurality of disc records are carried in a storage magazine 5 and in which the records are successively removed from the said magazine, placed upon a turn table for playing, removed from the said turn table, reversed, replaced thereon for playing the opposite side and then returned to the storage magazine.

It has become common practice for manufacturers of phonograph records to record a long composition such as an opera or a symphony upon a series of records having 15 portions of the composition upon both sides of each record. Ordinarily the proper sequence for playing the records to reproduce the original composition is to play both sides of a given record before proceeding to the 23 next.

The principal object of the present invention is to produce a phonograph which automatically reproduces the successive portions of such a composition in the proper sequence.

Another object of the invention is to provide such a phonograph in which records of either or both of the common standard sizes may be used at the same time.

One feature of the invention by which 30 these objects are attained is the provision of means for removing the record from the turn table, reversing the same and placing it upon a record support which may be automatically actuated to return the record to the turn 38 table for playing the opposite side, if only one side has been played, or may be actuated for returning the record to the storage magazine if both sides have been played.

Another feature of the invention resides 40 in the specific form of apparatus used for actuating the said record-manipulating mechanism.

Another feature of the invention resides 45 in the provision of a novel means for controlling the position of the tone arm for the start of playing the different sizes of records. This is accomplished by providing trackways at different elevations for the larger and smaller records by means of which the 50 larger records will travel at a higher eleva-

tion than the smaller records in approaching the turn table so that the larger records may be brought in contact with actuating mechanism for properly positioning the tone arm for playing said records.

Another feature of the invention resides in the fact that the said actuating mechanism engages the upper surface of the records rather than the edge of the record. It is, therefore, not necessary that the edge of 60 the record be located with absolute accuracy to insure engagement with said actuating mechanism. Accordingly, records of different manufacturers which vary considerably in outside diameter may be used.

Another feature of the invention resides in the fact that in each movement of the record wherein accurate placing of the record is required at the termination of the movement, the movement is accomplished by 70 engagement with the centering hole of the record rather than the edge of the record. Therefore, the actual diameter of the record plays no part in the accurate placing thereof and records may be used which vary greatly 75 in their outer diameters.

Another feature of the invention resides in the provision of a novel form of mechanism for imparting to the record at one portion of its travel a greater total movement than that imparted to a record in another portion of the travel by the same actual movement of the record-manipulating mechanism.

Another feature of the invention consists 85 in the novel form of supports for the stack of records in the storage magazine, the said supports being rotatably mounted and being rotated from beneath the stack of records to allow a record to be returned to the 90 bottom of said stack.

Another feature of the invention resides in the provision of a centering pin for engaging the centering holes of all of the records in the storage magazine during the return of a record thereto whereby all of said records are accurately maintained in position.

Other objects and features will be appar- 100

ent from the accompanying drawings and the following description and claims:

Fig. 1 is a plan view of the phonograph. Fig. 2 is a side elevation thereof. Fig. 3 is a fragmentary elevational view illustrating the operation of the record-reversing mechanism. Fig. 4 is a side elevational view of the phonograph showing the opposite side to that illustrated in Fig. 2. Fig. 5 is a sectional view of the machine taken on the lines 5—5 of Figs. 1 and 2. Fig. 6 is an elevational view of the end of the machine containing the record-storage magazine with parts cut away to show other parts in detail. Fig. 7 is a fragmentary plan view of a portion of the record-moving apparatus. Fig. 8 is a plan view of a portion of the apparatus used to locate the tone arm for the playing of the larger size of records. Figs. 9 and 10 are elevational views of the parts shown in Fig. 8 in the relative positions assumed at different points in the cycle of operation.

25 Frame and turn table power mechanism

The frame of the machine includes pairs of longitudinal members 10, 11 and 12, lateral members 13, 14 and 15 at one end and 16, 17 and 18 at the other end, vertical members 19, 20, 21, 22, 23, 24, 25, 26 and 27 at one side of the machine and 28, 29, 30, 31, 32, 33, 34, 35 and 36 at the other side together with other minor frame members hereinafter mentioned. An electric motor 37 is supported by a resiliently-mounted platform 38 carried by frame members 10 and 13. The said motor has a pulley 39 about which is trained a belt 40. The belt 40 is also trained about a pulley 41 carried 40 by a horizontal shaft 42 carried in bearings 43 and 44 suitably mounted upon frame members 27 and 12 respectively. The shaft 42 also carries a worm 45 engaging a worm wheel 46 mounted upon a shaft 47. The 45 said shaft is supported at one end upon a bracket 48 supported upon the frame member 11 and is supported at its opposite end upon a bearing 49 carried by the frame members 11 and 12. A pinion 50 is fixedly 50 carried by the said shaft and engages a gear 51 supported upon a shaft 52. The shaft 52 is supported at one end upon a portion of a frame 53 in turn carried upon a plate 54 extending between and supported 55 by the frame members 12. The frame 53 carries a vertical spindle 55 in turn supporting a turn-table 56 adapted to receive a record 57 for playing. The spindle 55 is rotated by the shaft 52 by means of a train of 60 gears indicated generally by the numeral 58. The said train of gears may be replaced by a spring motor continuously wound by the shaft 52 or by the type of turntable driving mechanism disclosed in my copending application Serial No. 386,609, filed August 17,

1929. It is to be noticed that the motor 37 and turntable are continuously operated.

Power Mechanism for moving carriage (80)

The shaft 47 has fastened thereto a clutch member 59. A clutch member 60 is also carried by the said shaft free to rotate thereon and a pinion 61 is formed integral with said clutch member 60. A lever 62 is pivotally carried upon the bracket 48 by means of a vertical screw 63. The said lever carries an upwardly-extending fork 64 engaging the clutch member 60 for moving the same into and out of engagement with the clutch member 59. The outer end of the lever 62 is engaged by the upper end of a lever 65 pivotally mounted by means of a pin 66 upon the frame member 23. The lower end of the lever 65 is pivotally connected to the armature 67 of the electric magnet 68, in turn carried upon the frame member 23. By means of this construction, the energizing of the electromagnet serves to bring the clutch members 59 and 60 into engagement. A spring 69 interposed between the lever 65 and the frame member 23 operates to disengage the said clutch member when the electro-magnet 68 is de-energized.

The sprocket 61 carries a chain 70 which is also trained about a sprocket 71 carried by a stub shaft 72 supported upon one of the frame members 12. A sprocket 73 is likewise carried on the said stub shaft and carries a chain 74 engaging a sprocket 75 upon a similar chain 76. The chain 74 carries a roller 77 adapted to engage a pair of downwardly-extending arms 78 and 79 supported upon a movable carriage 80. The carriage 80 is in turn supported by flanged rollers 81 adapted to roll upon the frame members 12. By means of this construction, the energizing of the electromagnet 68 engages the clutch members 59 and 60 actuating the chain 74 to move the carriage 80 upon the frame members 12. For convenience, the travel of the carriage 80 to the left, referring to Figs. 1 and 2, will be referred to hereinafter as the "forward" travel. The travel to the right will be called the "reverse" travel.

Power mechanism for moving cam shaft (88)

The stub shaft 76 also carries a pinion 82 engaging a gear 83 carried upon a stub shaft 84. The said stub shaft also carries a sprocket 85 having a chain 86 engaged therewith. The said chain engages a sprocket 87 carried upon a cam shaft 88. The shaft 88 extends through the machine and is supported at one end upon frame members 21 and 22 and at the opposite end upon frame member 33. The sizes of the sprockets and gears included in the drive for shaft 88 are

so chosen that the said shaft makes a complete revolution while the roller 77 makes two complete forward and reverse travels. Thus the carriage 80 makes two complete cycles of movement while the shaft 88 makes one. During the first cycle of carriage travel a record is moved from the storage magazine to the turn table and a record just played is moved from the turn table, reversed and placed in position to be returned to the magazine while the cam shaft 88 makes a half revolution. This cam shaft movement is hereinafter referred to as the "first half revolution". During the second cycle of carriage travel, a record is moved from the turn table, reversed, and returned thereto while the cam shaft 88 makes another half revolution. This cam shaft movement will be called the "second half revolution". The cam shaft 88 carries a plurality of cams for actuating the various record-controlling mechanisms to be herein-after described. The shaping of these cams controls the actions of said mechanisms in timed relation.

Moving record from storage magazine to turn table

In Figs. 1 and 6 is illustrated a pile of records 89 supported upon a pair of support members 90, each carried upon the upper end of a vertical stem 91. For convenience, the portion of the machine containing the pile of records 89 will be hereinafter referred to as the "storage magazine". As illustrated in the drawings, the pile of records may contain both the common ten-inch and twelve-inch sizes. The stems 91 pass downwardly through closely fitted openings in a frame member 92 supported upon the frame members 11 and thence through similar openings in a frame member 93 supported upon the frame members 10. A shoulder 94 is formed on the lower end of each of the stems 91 and normally abuts against the upper surface of the frame member 93 for supporting the weight of the stems 91 and the pile of records. At the proper time for the removal of a record from the storage magazine, a pair of cams 95 on the shaft 88 engage a pair of arms 96, each freely mounted upon a shaft 97 supported upon the frame members 20 and 35. The arms 96 are fitted with upwardly-extending portions 98 engaging the underside of collars 99 carried upon the stems 91. Thus when the cams 95 engage the arms 96 to elevate the same, the stems 91 and the records 89 are elevated to the position illustrated in Fig. 6.

The traveling carriage 80 has pivotally attached thereto an arm 100. The said arm carries at its outer end a pivotally-mounted member 101 adapted to rest upon the upper surface of the uppermost record in the pile when said records are elevated to the posi-

tion illustrated in Fig. 6. When the said records are lowered to bring the shoulders 94 into engagement with the frame member 93, the member 101 will be maintained at a level above the surface of the uppermost record. The member 101 carries on its undersurface a ratchet-shaped tooth 102 adapted to engage the centering hole in the uppermost record. At the completion of playing of a record, the electromagnet 68 is energized by means to be hereinafter described. The clutch members 59 and 60 are thrown into engagement thereby and the roller 77 begins its circuit about the chain 74. The said roller engages the arm 79 carrying with it the carriage 80. In the motion of the carriage 80, the uppermost record is removed from the storage magazine by means of the tooth 102 and is placed in position above the turn table 56.

Positioning tone arm for two sizes of records

The plate 54 adjacent the turn table is fitted with guideways 103 having record-supporting surfaces 104 at one level and record-supporting members 105 at a higher level. If the record being moved is a ten-inch record, it rests upon the surfaces 104 and is guided by the members 105. If the said record is a twelve-inch record, it rests upon the members 105 and is guided by a pair of ribs 106. A sloping portion 107 of each of the members 103 serves to guide the larger size records to the upper surface of the members 105. Thus the larger size records approach the turn table at a higher level than the smaller size.

A lever 108 is pivotally supported upon a pin 109 and carries a substantially hemispherical roller 110. At the opposite end of the said lever there is carried a member 111 supporting a pair of tubular members 112 and 113. The tubular member 112 contains a cylindrical rod 114 and a similar rod 115 is contained within the tubular member 113, rod 114 being longer than rod 115. A tone arm of common form 116 is universally mounted upon a bracket 117 carried by the frame member 112. The said tone arm carries a reproducer 118 of a common form and a needle 119 for engaging the record. The said reproducer may be electrically connected to any common type of amplifier and speaker for reproduction of the sound. A stem 120 is carried by the arms 78 and 79 of the carriage 80. When a twelve-inch record is moved to the turn table, the upper surface of the record engages the roller 110 thereby moving the lever 108 and the member 111 carried thereby to bring the tubular member 113 into the path of travel of the stem 120. In the movement of the carriage 80 the said stem enters the tubular member 113 pushing the rod 115 therethrough. The

said rod engages a collar 121 carried upon a vertical stem 122 attached by means of a ball and socket joint 123 to the tone arm 116. The lengths of the member 115 and the stem 120 are so chosen that the engagement of the said member with the collar 121 moves the tone arm to the proper position for the start of playing of a twelve-inch record.

If a ten-inch record is being moved to the turn table, the said record travels at the lower level and does not engage the roller 110. The said roller is, therefore, maintained in its lowered position by means of a spring 124 interposed between the lever 108 and the plate 54. In this position the tubular member 112 is in the path of travel of the stem 120. The said stem, therefore, enters the tubular member 112, engages the shorter rod 114, whereby the tone arm is moved a shorter distance to the proper position for the start of playing of a ten-inch record. Thus the engagement of the roller 110 with the upper surface of a twelve-inch record determines the position at which the tone arm will be moved for the start of playing of that sized record.

Lowering record onto turn table

Adjacent the turn table 56 there are located a pair of vertically-movable members 125 having their upper surfaces formed as a continuation of the record-carrying surfaces 104 and 105 and the guide rib 106. Each of the members 125 is carried by a stem 126 and each of said stems is guided in a bearing member 127 supported on one of the frame members 11. The lower end of each of the stems 126 is pivotally connected to the end of a lever 128 in turn pivotally mounted upon the frame member 11 by a pin 129. The levers 128 have downwardly-extending portions 130 each carrying a roller 131 engaging a cam 132 carried by the shaft 88. During the movement of a record to the turn table, the members 125 are normally maintained at the elevation at which their upper surfaces form a continuation of the before-mentioned record-supporting surfaces. At this elevation, the record is propelled by the lug 102 until it comes to rest upon the members 125 with its center above the centering pin 133 of the turn table. At this position, the cams 132 operate to allow the lowering of the members 125 by gravity to the position illustrated in Fig. 5 at which position the record 57 rests upon the turn table 56 and the members 125 are free of the edge of the record. Thereafter, the continued travel of chain 74 returns the carriage 80 to the initial position illustrated in Fig. 2.

Lowering tone arm

During the latter part of the carriage 65 travel, a cam 134 carried upon the shaft 88

acts to allow the lowering of a lever 135 pivotally carried upon the shaft 97. The said lever carries at its outer end the lower end of the rod 122, thus the lowering thereof allows the lowering of the tone arm 70 to bring the needle 119 into engagement with the record for playing the same. Both the lower and upper ends of the stem 122 are fitted with ball and socket joints 123 and 136 so that the needle is free to follow the sound groove of the record. The cam 134 acts to maintain the tone arm in elevated position throughout all of the travel of the carriage 80 so that no interference is possible between tone arm and carriage. 75 80

End of first cycle and start of record

Upon the completion of travel of the carriage and the first half revolution of shaft 88, the electromagnet 68 is deenergized by the opening of a suitable switch actuated by the shaft 88 not shown in the drawings. The clutch members 59 and 60 are thereby disengaged and motion of the carriage and the shaft 88 ceases. Upon the completion of playing of record, a mercury switch 137 is tripped by suitable mechanism such as that described in detail in my copending application Serial No. 363,776, filed May 17, 1929. The said switch is connected to the electromagnet 68 and energizes the same for a repetition of the movement of the chain 74 and for the second half revolution of shaft 88. At the start of the second half revolution, the cams 95 are in such position that the stems 91 are not elevated to the position illustrated in Fig. 6. Therefore, the member 101 does not engage the upper record in the storage magazine and no record is removed from the said magazine to the turn 90 95 100 105 table.

Removal of record from turn table

The carriage 80 carries a bearing member 138 in which is freely mounted a horizontal stem 139. The said stem carries a finger 140 having a downwardly-extending portion 141 adapted to rest upon the centering pin 133 of the turn table. During the time that the roller 77 is moved from the position shown in Fig. 2 to engage the arm 79, the cams 132 operate to elevate the members 125 to lift the record just played above the centering pin 133. The centering hole of the record then engages the downwardly-extending portion 141 and the record is moved thereby from the turn table by the movement of the carriage 80. 110 115 120 125

Reversing the record

At the edge of the plate 54 is an apron 142 pivotally carried upon a horizontal shaft 143, see Figs. 2 and 3. The shaft 143 has attached thereto an arm 144 to which is pivotally attached a link 145. The lower end 130

of link 145 is pivotally attached to a lever 146 in turn carried upon a pin 147 upon the frame member 22. The lever 146 has a downwardly-extending portion 148 engaging a cam 149 upon the shaft 88. The upper surface of the apron 142 is formed with guideways 150 and 151 forming a continuation of the record-guiding surfaces 103 and 106. As shown in Fig. 1, the said guideways are converging in form. As the record is moved from the turn table onto the apron 142, the cam 149 operates to cause the said apron to tilt into the position illustrated in Fig. 3. During the tilting, the converging 15 guideways prevent the record from slipping from the apron.

The stem 139 carries a downwardly-extending arm 152 in turn carrying a roller 153. In the travel of the carriage 80, just prior to the tilting of the apron 142, the roller 153 strikes a downwardly-hanging link 154 pivotally carried by means of a pin 155 upon the side of the frame member 12, said pin being provided with a shoulder to prevent it from swinging rearwardly while permitting it to swing forwardly. This engagement causes rotation of the stem 139 and elevation of the finger 140 out of engagement with the centering hole of the record. During the remainder of the travel of the carriage 80, the roller 153 runs upon a trackway 156 likewise carried upon the frame member 12. The finger 140 is thereby maintained in its upraised position until a point is reached close to the end of said travel whereupon the roller 153 reaches the end of the trackway 156 and dropping therefrom permits the member 140 to resume its horizontal position, in which position it is maintained by a pin 157 engaging a shoulder 158 upon the bearing member 138.

A pair of irregularly-shaped arms 159 are carried upon a shaft 160 in turn supported by frame members 24 and 31. The shaft 160 also carries an arm 161 to which is pivotally connected a link 162 in turn pivotally connected to a lever 163. The lever 163 is freely supported upon a shaft 164 extending between the frame members 10 and carries a pin 165 engaging a cam 166 carried upon the shaft 88. A tension spring 167 extends between the levers 146 and 163 and serves to maintain the same in engagement with their respective cams. By this mechanism, the action of the cam 166 serves to rock the shaft 160 and elevate the arms 159. The tilting of the apron 142 brings the edges of the record into engagement with a pair of wires 168 strung between the members 14 and 17. When the record has reached this position, the cam 166 operates to elevate the arms 159. The arms then engage the record 169 moving it to the position illustrated in Fig. 3. At this position, it is supported by the wires 168 and its lower edge is in con-

tact with a pair of upwardly-extending stationary members 170. The said members prevent the lower edge of the record from sliding upon the wires 168. The cam 166 then operates to lower the arms 159 allowing the record to follow the same. The record then comes to rest upon a pair of vertically-movable record supports 171 with the opposite side to that previously played uppermost, said supports being shown in 75 their lowermost position in Fig. 3.

Returning record to turn table for playing second side

Each of the record supports 171 is carried upon a vertical stem 172 mounted in suitable bearings on the frame members 10 and 11. A horizontal member 173 connects the said stems and has attached thereto a short length of chain 174. The chain 174 is attached at its upper end to one arm of a bell crank member 175 supported upon a shaft 176 carried by frame members 25 and 30. The opposite arm of the bell crank 175 is connected to a link 177 in turn connected 85 to the upper end of a lever 178 freely carried upon the shaft 164. The lever 178 carries a roller 179 engaging a cam 180 carried upon the shaft 88. When the record has been placed in position upon the supports 90 171, the cam 180 operates through the linkage just described to elevate the said supports to the level of the plate 54. During such elevation the apron 142 is held in lower and rearward position by cam 149 free of 95 the movement of supports 171 which terminate short thereof. The entire operation of reversing a record and re-elevating the same takes place during the latter part of the forward travel of the carriage and during 100 the time the roller 77 travels from its engagement with arm 79 to engage arm 78. Upon the commencement of return travel of the said carriage, the finger 140 engages the centering hole of the record and further 105 movement returns the same to the support members 125 above the turn table. It is to be noticed that the upper surface of the members 171 is formed to supply a continuation of the record-supporting surfaces 104 and 105 and the guiding surfaces 106. It is also to be noticed that during the elevation of the record, the apron 142 remains in its downwardly-tilted position and thereby prevents interference with the movement of the record support and record. During the return of the carriage, the roller 153 passes beneath the trackway 156 and the pivoted member 154 is moved thereby from the path of the roller. The finger 140, therefore, 110 maintains its horizontal position during the entire return travel. When the record is again in place upon the support members 125, the said members are lowered as before 115 to place the record upon the turn table. 120

*Placing tone arm for playing second side
of record*

During the removal of a record from the 5 turn table, the reversing of the same and the return thereof to the turn table for playing the second side, no record engages the roller 110 even though the record being handled may be a twelve-inch record. 10 Therefore, the stem 120 enters the tubular member 112 and the tone arm is returned to the initial position for playing a ten inch record. If a twelve-inch record is being returned to the turn table, it is supported 15 upon the upper record-supporting members 105. At that position, it engages a hemispherical roller 181 carried upon the end of a lever 182 pivotally mounted at 183 upon the plate 54. The said roller engages the 20 upper surface of the record in the same manner as the roller 110 and the lever 182 is moved thereby, in opposition to the force of a spring 184 interposed between said lever and the plate 54. The outer end of the lever 25 182 carries a tubular member 185 within which is carried a slidable stem 186 fitted with cotter pins 187 and 188. A washer 189 surrounds the stem 186 and abuts against the end of the tubular member 185. A similar washer 190 abuts against the pin 188. A helical spring 191 surrounds the stem 186 and is interposed between said washers. The carriage 80 carries a bracket 192 upon which is pivotally mounted an irregularly-shaped member 193. The said member 193 is yieldingly maintained in contact with the bracket 192 by means of a conical spring 194. The bracket 192 has a depression formed therein in which is placed a ball 196. The member 30 193 has corresponding depressions 197 and 198 adapted to engage a portion of said ball extending beyond the depression in bracket 192. The member 193 also carries stop pins 199 and 200 adapted to engage the bracket 45 192 for limiting the movement of the member 193 about its pivotal support. In Fig. 9, the member 193 is shown positioned with the stop pin 200 engaging the bracket 192 and the ball 196 engaging the depression 197. The said ball yieldingly maintains the member 193 in the said position. Upon the application of a predetermined force to rotate the member 193, the spring 194 yields allowing the ball to escape from the depression 197 and allowing the member 193 to move into the position illustrated in Fig. 2 wherein the ball 196 engages the depression 198 and the stop pin 199 engages the bracket 192. 50 In the return travel of the carriage 80 during the movement of a record from the supporting members 171 to the turn table, the member 193 is normally in the position illustrated in Fig. 9. If the record being 55 transferred is a twelve-inch record, the up-

per surface thereof engages the roller 181, moving the lever 182 to bring the stem 186 in line with the travel of the member 193, as illustrated in Fig. 9. The member 193 thereupon engages the end of the stem 186 moving the same to engage the end of a lever 201 pivotally carried upon the bracket 117. The opposite end of the said lever engages the vertical rod 122 and moves the tone arm to the proper position for starting the playing of a twelve-inch record. In this position, the tone arm engages a rigid stop, not shown in the drawings, and the continued travel of the carriage 80 exerts sufficient pressure on the member 193 to cause its movement to the position illustrated in Fig. 2. The tone arm is then lowered by the mechanism previously described and the playing of the record begins.

If the record being moved is a ten-inch record, there is no engagement with the roller 181 and the stem 186, therefore, remains in the position illustrated in Figs. 1, 2 and 10. In this position, the member 193 engages the washer 190 as shown in Fig. 9. 10. The stem 186 is moved thereby, but, since it is at the higher elevation, it does not engage the lever 201 and no added movement of the tone arm takes place. Upon the spring 191 becoming coil-bound, sufficient pressure is exerted to move the member 193 to the position shown in Fig. 2.

In the position shown in Fig. 2, a cut away portion 202 of the member 193 is uppermost. Therefore, when the carriage 80 again moves forward, the said member will not interfere with the stem 186 and washers 189 and 190, even though the latter are moved by the removal of a twelve-inch record from the turn table. At the completion of the forward travel of the carriage 80, a flexible spring member 203 carried upon the bearing 43 engages a shoulder 204 on the member 193 and, upon the commencement of the return travel of the carriage 80, the member 193 is returned thereby to the normal position illustrated in Fig. 9.

End of second cycle

When the record has again been placed in position on the turn table, the tone arm is lowered for playing the record as before. The electromagnet 68 is deenergized at the end of the second half revolution of cam shaft 88 to stop the carriage and cam shaft. 110

Second removal of record from turn table

Upon the completion of playing of the second side of the record, the mercury switch 137 is actuated to energize the electromagnet 68 to initiate the travel of the carriage 80 and to repeat the first half revolution of the shaft 88. A record is moved thereby from the storage magazine to the turn table in the same manner as previously described and at 115

the same time the finger 140 removes the record just played from the turn table to the apron 142. When the last-mentioned record has reached the apron 142, the finger 140 is elevated by the engagement of the roller 153 with the pivoted link 154. The said roller thereupon rides upon the trackway 156 and, during the travel of the roller upon said trackway, a cam 205 upon the shaft 88 engages a lever 206 which is pivotally carried upon the frame member 35. The opposite end of said lever engages a vertically-slidable member 207 upon the upper end of which is carried a pair of track portions 208 and 209. The operation of the said cam thereupon elevates the said trackways 208 and 209 into position to form a continuation of the trackway 156. The said trackways remain in place during the remainder of the forward travel of the carriage 80 and during the entire return travel thereof. The member 140 is, therefore, maintained in its upraised position during this entire period. The trackway 209 is formed with a downwardly-curved portion 210. At the end of the return travel of the carriage 80, the roller 153 reaches this downwardly-curved portion 210 and the finger 140 is thereby gently lowered to bring the downwardly-extending portion 141 thereof to engagement with the centering pin 133 of the turn table. Thereupon the cam 205 operates to return the trackways 208 and 209 to their initial position.

55 *Second reversal of record and return to magazine*

When the record just played has been placed upon the apron 142, the said apron and the arms 159 are operated as before to reverse the record and place the same upon the record-supporting members 171 with the side first played uppermost. At this point in the cycle of operation, when the cam shaft 40 is in its first half revolution, the said supporting members are not elevated but remain in their lowermost position. In this position, the said members are aligned with a trackway 211 having a lower portion 212 adapted to receive and guide a ten-inch record and an upper portion 213 adapted to receive and guide a twelve-inch record.

The carriage 80 carries a downwardly-extending arm 214 having a roller 215 thereon engaging the lower edge of one of the frame members 11. The arm 214 has a horizontally-extending portion 216 extending inwardly to the center of the machine. The said portion 216 carries a horizontal member 217 extending longitudinally of the machine. The member 217 carries at one end an upwardly-extending piece 218 extending approximately to the level of the record-supporting trackway 212. The member 217 also carries upwardly-extending lugs 219

pivotedly supporting a pin 220 to which is attached a downwardly-extending member 221 and a pair of upwardly-curved fingers 222. The downwardly-extending member 221 carries a weight 223. The upwardly-extending fingers 222 extend on opposite sides of the piece 218 as illustrated in Figs. 4 and 7.

At the time the record is placed upon the supporting members 171, the carriage 80 has completed its forward travel and the downwardly-extending member 221 has been moved thereby to a position illustrated by broken lines in Fig. 4. In the said position, the member 221 engages a horizontal member 224 attached to the frame member 14. At this position, the fingers 222 are thrown backwardly, as illustrated, to a position at which they will engage the edge of a twelve-inch record placed upon the supporting members 171. During the return travel of the carriage 80, the fingers 222 engage the edge of the record and propel the same from the supporting members 171 to the trackway 211. In this movement, the downwardly-extending member 221 is freed from the horizontal member 224 and the weight 223 causes the same to assume a nearly vertical position. As the carriage 80 approaches its initial position, the downwardly-extending member 221 engages a laterally-extending frame member 225 supported upon vertical frame member 226. This engagement causes the fingers 222 to be tilted forwardly to the position shown in solid lines in Fig. 4. It is evident, therefore, that this action of the fingers 222 causes the record to be propelled through a greater distance than the actual travel of the carriage 80. This is necessary for a purpose to be hereinafter mentioned. Upon the next forward travel of the carriage 80, the record is left in position upon the trackway 211.

The member 217 has an upwardly-extending portion 227 upon which is pivotally mounted a finger 228 having a ratchet-shaped tooth 229. In the said forward travel of the carriage 80, the tooth 229 passes the centering hole in the record due to the fact that the record has been moved a greater distance than the actual travel of the carriage 80, as previously described. In the succeeding return travel of the carriage, the tooth 229 engages the centering hole of the record and propels the same along the trackway 211 to a position exactly beneath the pile of records 89 in the storage magazine.

Beneath the storage magazine a vertically-extending stem 230 is slidably mounted in frame members 92 and 93. The said stem carries at its upper end a plate 231 and a centering pin 232. A chain 233 is attached to the stem 230 and passes over a sprocket 234. The opposite end of the chain is attached to a lever 235 pivotally mounted upon

the shaft 164. The lever 235 carries a roller 236 engaging a cam 237 carried by the shaft 88. During the forward travel of the carriage 80, after a record has been left in position beneath the storage magazine, the cam 237 engages the roller 236 to move the lever 235 and elevate the stem 230, the plate 231 and the centering pin 232. The pin 232 engages the centering hole in the record and 5 passes upwardly engaging the centering holes of all of the records in the storage magazine. The plate 231 carries with it the record just positioned beneath the magazine and brings the same into engagement with 10 the undersurface of the supporting members 90 slightly elevating the same with their supporting stems 91.

Each of the collars 99 carried by the said 20 supporting stems carries an arm 238 to which is attached a link 239 in turn attached to the upper end of a lever 240. Each of the levers 240 carries a roller 241 engaging a cam 242 upon the shaft 88. Upon the engagement of the last-mentioned record with 25 the undersurface of the supporting members 90, the said cams operate to rotate the stems 91 removing the members 90 from beneath the stack of records. During the said movement, the stack of records is supported upon 30 the plate 231 and held in position by the centering pin 232. When the members 90 have been moved free of the stack of records, the stems 91 are free to drop, bringing the members 90 to a level beneath the lowermost 35 record in the stack. When this takes place, the cam 242 operates to permit the return of the members 90 to their position beneath the stack under the influence of a pair of tension springs 243 each connected to one of 40 the levers 240 and one of the vertical frame members.

By means of the apparatus described, each record, whether of the ten-inch or twelve-inch size, is moved from the storage magazine 45 to the turn table, played on one side, reversed, played on the opposite side and returned to the underside of the pile of records in the magazine. All of the movements of the records, with the exception of 50 the movement from the supporting members 171, is accomplished by engagement with the centering hole of the record. The records, therefore, are accurately positioned at the end of each of said movements without 55 regard to their size. In the movement from the supporting members 171, there is no need of accurate positioning at the termination of the movement. It is only necessary that the record be moved far enough to be engaged 60 by the tooth 229. This is accomplished by means of the fingers 222 which give the records a greater travel than the actual travel of the carriage 80 thus insuring that the record will be engaged by the tooth 229 irrespective of its size.

The invention claimed is:

1. In an automatic phonograph the combination of a rotatable playing turn table, a record-supporting member normally maintained at a lower elevation than said turn 70 table, mechanism for removing said record from said turn table upon the completion of playing one side, reversing the same and placing it with the opposite side uppermost upon said record support, mechanism operable thereafter to elevate said support substantially to the level of the turn table, and other mechanism adapted to move said record from said support to said turn table for 75 playing the opposite side. 80

2. In an automatic phonograph the combination of a record storage magazine, a turn table adapted to receive a record for playing, a record-supporting member normally positioned at a lower level than that of said 85 turn table, mechanism automatically operable upon the completion of playing of one side of a record to remove the same from said turn table, reverse the same and place it upon said supporting member with the 90 opposite side uppermost, mechanism automatically operable thereafter to elevate said support member substantially to the level of said turn table, mechanism operable there- 95 after to remove said record from said sup- 100 porting member to said turn table for play- 105 ing the opposite side thereof, and other mechanism automatically operable upon the completion of playing said second side to 110 return said record to said magazine. 115

3. In an automatic phonograph the combination of a record storage magazine, a turn table adapted to receive a record for playing, a record-supporting member movable between an upper and a lower position, mechanism automatically operable upon the completion of playing of one side of a record to remove the same from the turn table, reverse the same and place it upon said sup- 110 porting member with the opposite side up- 115 permost, means for moving said support member between its upper and lower posi- 120 tions, mechanism operable when said sup- 125 port member is in its upper position to move the record therefrom to said turn table for 125 playing the opposite side, and other mecha- 130 nism operable when said member is in its lower position to move the record therefrom for return to said storage magazine.

4. In an automatic phonograph the combination of a record storage magazine, a turn table adapted to receive a record for playing, a record-supporting member movable between an upper and a lower position, mechanism automatically operable upon the completion of playing of one side of a record to remove the same from the turn table, reverse the same and place it upon said sup- 120 porting member with the opposite side up- 125 permost, means for moving said support 130

- member between its upper and lower positions, mechanism operable when said support member is in its upper position to move the record therefrom to said turn table for 5 playing the opposite side, other mechanism operable when said member is in its lower position to move the record therefrom for return to said storage magazine, and mechanism operable simultaneously with said last- 10 mentioned mechanism to move another record from said magazine to said turn table. 5. In an automatic phonograph the combination of movable supporting means for a stack of records, a playing turn table, a 15 movable carriage, motor driven means for moving said carriage, a record-engaging member carried by said carriage and adapted to engage a record in a stack carried by said supporting means when said supporting 20 means is in a predetermined position, said member being adapted to move said record from said stack to said turn table in the movement of said carriage, and mechanism adapted to move said supporting means from 25 said predetermined position upon alternate movements of said carriage, whereby no record is engaged by said record-engaging member for removal from said stack upon said alternate movements of said carriage. 30 6. In an automatic phonograph the combination of vertically-movable supporting means for a stack of records, a playing turn table, a movable carriage, motor driven means for moving said carriage, a record- 35 engaging member carried by said carriage and adapted to engage the uppermost record in a stack carried by said supporting means when said supporting means is in its uppermost position, said member being 40 adapted to move said record from said stack in the movement of said carriage, and mechanism adapted to move said supporting means from its uppermost position upon alternate movements of said carriage, whereby 45 no record is engaged by said record-engaging member upon said alternate carriage movements. 7. In an automatic phonograph the combination of a rotatable turn table, mechanism 50 for moving records to said turn table for playing, said mechanism being adapted to move records of different sizes, a tone arm, mechanism associated with said record-moving mechanism normally operable to place said tone arm in position for the start of playing a record of one size, and means engageable with the upper surface of a record of different size adapted to actuate said tone arm placing mechanism for placing 55 said tone arm in position for the start of playing thereof. 8. In an automatic phonograph the combination of a playing turn table, mechanism for moving records to said turn table for 60 playing, said mechanism being adapted to 65 move records of different sizes, a tone arm, mechanism normally operable during the movement of a record to said turn table for placing said tone arm in position for the start of playing a record of one size, a member adapted to engage the upper surface of a record of a different size during its movement to said turn table, and mechanism associated with said member for imparting an additional movement to said tone arm to place the same in position for the start of playing thereof. 70 75 80 85 90 95 100 105 110 115 120 125 130
- move records of different sizes, a tone arm, mechanism normally operable during the movement of a record to said turn table for placing said tone arm in position for the start of playing a record of one size, a member adapted to engage the upper surface of a record of a different size during its movement to said turn table, and mechanism associated with said member for imparting an additional movement to said tone arm to place the same in position for the start of playing thereof. 70 75 80 85 90 95 100 105 110 115 120 125 130
9. In an automatic phonograph the combination of a turn table, record-moving mechanism for moving records to said turn table for playing, said mechanism being adapted to move records of different sizes, a playing stylus, a stylus-moving member, an actuating member carried by said record-moving mechanism and movable therewith, a pair of intermediate members selectively interposable between said stylus-moving member and said actuating member, said intermediate members being proportioned so that when one is so interposed said actuating member acts therethrough in the movement of said record-moving mechanism to actuate said stylus-moving member to place said stylus in position for the start of playing of one size of record and when the other is so interposed said actuating member acts therethrough to place said stylus in position for the start of playing a second size of record, and means automatically actuatable dependent upon the size of record being moved to said turn table for selectively interposing the proper intermediate member for that size of record. 90 95 100
10. In an automatic phonograph the combination of a turn table, record-moving mechanism for moving records to said turn table for playing, said mechanism being adapted to move records of different sizes, a playing stylus, a stylus-moving member, an actuating member carried by said record-moving mechanism and movable therewith, an intermediate member normally interposed between said stylus-moving member and said actuating member whereby said actuating member acts therethrough in the movement of said record-moving mechanism to actuate said stylus-moving member to place said stylus in position for playing a smaller size of record, a second intermediate member, and mechanism engageable with the upper surface of a larger size of record in its movement toward said turn table and adapted upon such engagement to remove said first intermediate member from its normal position and to interpose said second intermediate member between said actuating member and said stylus-moving member, said second intermediate member being so proportioned that said actuating member acts therethrough in the movement 105 110 115 120 125 130

of said record-moving mechanism to place said stylus in position for playing the larger size of record.

11. In an automatic phonograph the combination of a storage magazine adapted to contain records of different sizes, a playing turn table, record-supporting members extending at different horizontal levels between said magazine and said turn table, to support a smaller record at one level and a larger record at another level, automatic means for propelling records along said record-supporting members, a tone arm, mechanism normally operable in the movement of said records for placing said tone arm in position for the start of playing of one size of record, and other mechanism engageable with a record carried at the higher level for actuating said tone arm placing mechanism for placing the said tone arm in position for the start of playing of the other size of record.

12. In an automatic phonograph the combination of a movable carriage adapted to move a record through a predetermined travel, a pivotally-mounted finger carried by said carriage and adapted to engage another record for propelling the same in the motion of the said carriage, and means for moving said finger upon its pivotal mounting whereby said second record is propelled through a greater distance than the predetermined travel of said first record.

13. In an automatic phonograph the combination of pivotally mounted members adapted to support a stack of records, means for placing a record beneath said stack, a vertically-movable member adapted to elevate said last-mentioned record toward the underside of the stack, mechanism operable thereafter for rotating said supporting members about their pivotal mountings for removing the same from said stack and for returning the same to position beneath said last-mentioned record.

14. In an automatic phonograph the combination of members adapted to support a stack of records, means for placing a record beneath said stack, a vertically-movable member adapted to elevate said last-mentioned record toward the underside of the stack, a centering pin carried by said last-mentioned member adapted to engage the centering holes of all of the records in said stack, and mechanism operable to move said supporting members from said stack and to place the same beneath said last-mentioned record.

15. In an automatic phonograph the combination of a turn table adapted to receive a record for playing, a centering pin on said turn table, a finger adapted to be positioned above said centering pin, means for elevating said record upon the completion of playing thereof to bring the centering

hole of said record into engagement with said finger, and mechanism for moving said finger to remove said record from said turn table.

16. In an automatic phonograph the combination of a turn table adapted to receive a record for playing, a centering pin on said turn table, a finger adapted to be positioned above said centering pin, means for elevating said record upon the completion of playing thereof to bring the centering hole of said record into engagement with said finger, mechanism for moving said finger to remove said record from said turn table, and mechanism operable thereafter to reverse said record and place the same in position for re-engagement of said finger with said centering hole for return of said record to said turn table by movement of said finger.

17. In an automatic phonograph the combination of a playing turn table, a movable finger adapted to engage the centering hole of a record for moving the same from said turn table, and mechanism operable thereafter to reverse said record and place the same in position for re-engagement of said finger with said centering hole for return of said record to said turn table by movement of said finger.

18. In an automatic phonograph the combination of a playing turn table, record-reversing mechanism, a movable finger adapted to engage the centering hole of a record, means for moving said finger when so engaged to move said record from said turn table to said record-reversing mechanism, mechanism operable thereafter to actuate said reversing mechanism to reverse said record, and means operable during said reversal to move said finger clear of said record and operable thereafter to bring said finger again into engagement with said centering hole for returning said record to said turn table.

19. In an automatic phonograph, the combination with a longitudinally fixed and horizontally rotatable turntable, of a reservoir for containing a stack of records in horizontal, contacting relation supported one upon the other, means for sliding a record horizontally from one side of the stack onto the turntable for the reproduction thereof, means for reversing the record and placing it on the turntable for playing the reverse side thereof without returning it to the stack, and means for thereafter returning the record to the other side of the stack with its original side up.

20. In an automatic phonograph, the combination with a horizontally disposed turntable fixed longitudinally of its center of rotation, of a reservoir, means for supporting a plurality of records therein one upon the other in horizontal relation, means for

sliding a record from the stack onto the turntable, means for removing the record from the turntable, overturning it and replacing it thereon without returning it to the stack, and means for thereafter returning said record to the stack with its original side up.

21. In an automatic phonograph, the combination with a horizontally disposed turntable fixed longitudinally of its center of rotation, of a reservoir, means for supporting a plurality of records therein one upon the other in horizontal relation, means for sliding a record from the stack onto the turntable, and means for removing the record from the turntable to one side thereof, overturning the same and returning it to the turntable in reversed position without returning it to the reservoir.

22. In an automatic phonograph, the combination with a horizontally disposed turntable fixed longitudinally of its center of rotation, of a reservoir, means for supporting a plurality of records therein one upon the other in horizontal relation, means for sliding a record from the stack onto the

turntable, and mechanism for sliding the record to one side of said turntable, overturning it, returning it to the turntable in reversed position, thereafter sliding it from the turntable and returning it to the reservoir with its original side up.

23. In an automatic phonograph, the combination with a horizontally disposed turntable fixed longitudinally of its center of rotation, of a reservoir, means for supporting a plurality of records of varying sizes therein one upon the other in horizontal relation, means for sliding a record from the stack onto the turntable, means for removing the record from the turntable to one side thereof, overturning the same and returning it to the turntable in reversed position without returning it to the reservoir irrespective of the size thereof, a reproducer, and means controlled by the size of the record for positioning the reproducer at the starting position thereon.

In witness whereof, I have hereunto affixed my signature.

THOMAS W. SMALL.
